UNITED STATES PATENT OFFICE.

OSWALD S. PULLIAM, OF PITTSBURG, PENNSYLVANIA, ASSIGNOR TO
PITTSBURGH EQUIPMENT COMPANY, OF PITTSBURG, PENNSYLVANIA, A CORPORATION OF PENNSYLVANIA.

CAR-BODY-UNDERFRAME CONSTRUCTION.

No. 833,086.

Specification of Letters Patent.

Patented Oct. 9, 1906.

Application filed May 19, 1906. Serial No. 317,805.

To all whom it may concern:

Be it known that I, OSWALD S. PULLIAM, a citizen of the United States, residing at Pittsburgh, in the county of Allegheny and State of Pennsylvania, have invented new and useful Improvements in Car - Body - Underframe Construction, of which the following is a specification.

This invention relates to improvements in car-body-underframe construction, and more particularly to the construction of transoms and center castings for said transoms constituting parts of the underframe.

In the accompanying drawings, which illustrate applications of my invention, Figure 1 is a top plan of a transom or body-bolster and a portion of the center sills of a car embodying my invention; Fig. 2, a part elevational view and part sectional view of the form of Fig. 1, showing the center casting in the form of a center bearing; Fig. 3, an elevational view of transom or body-bolster; Fig. 4, a part elevational and a part sectional view of a transom, showing center sills and center casting; and Fig. 5, a perspective view of a center casting fitted into the center sills.

Referring to the drawings, I have shown two forms of transoms. The form shown by Figs. 1, 2, and 3 is designed for a body-bolster and the form of Fig. 4 for an intermediate transom. In both forms the transom comprises a top member 1, a bottom member 2, and a vertical web 3, joining said top and bottom members. The bottom member 2 is cut away at its center, and the web is formed with two vertically-extending separated recesses 4 4, each located a short distance from the center of the transom. Forming the recesses 4 4, as particularly shown by Fig. 3, leaves a central web portion 5, constituting an integral compression member. The recesses 4 4 are adapted to receive draft members or center sills. In the drawings I have shown the center sills 6 in the form of channels, and while my invention is particularly designed for center sills of channel form it may be modified to adapt its use for center sills of other shapes. Said recesses 4 4 are each located between the central web portion 5 and ribs or flanges 7, which latter extend outwardly from and at right angles to the vertical web 3.

8 designates a center casting comprising a bottom plate 9 and two disunited upright members 10. In the employment of this center casting in connection with the transom or body-bolster shown by Figs. 1, 2, and 3 the bottom plate of the casting is formed with a center bearing member 11. When applied to the intermediate transoms, the bearing member 11 is omitted.

The center sills are located in the recesses 4 4 and extend through the same, as particularly shown by Fig. 1. The removable center casting 8 constitutes an important and characteristic feature of the present invention, providing a construction that may be readily applied to and removed from and be securely interlocked with the transom and center sills. It is adapted to be fitted into the recesses 4 4 and its upright members fitted into the center sills. As illustrated and as preferred, each upright member 10 is formed with slightly-inclined ledges 12 for the purposes of providing bearings for the top and bottom flanged portions 13 of the center sills. In addition to the parts mentioned I form two pockets 14 on the casting, which pockets are adapted to receive ribs or 80 projections 15 of the transom.

The upright members are of such form that when they are assembled with the center sills rectangular projections are completed, which projections completely fill the separated recesses of the transoms.

What I claim is—

1. In a car-body underframe, the combination with center sills in the form of channels, of a transom formed with separated recesses to receive the center sills, a removable center casting comprising a bottom member and two disunited upright members, said upright members located in the recesses of the transom, and means connecting the center 95 sills, upright members and transom.

2. In a car-body underframe, the combination with two center sills in the form of channels, a transom provided with separated recesses to receive the center sills, and a removable center casting having disunited upright members adapted to be fitted into the center sills.

3. In a car-body underframe, the combination with two center sills in the form of channels, a transom provided with separated

recesses to receive the center sills, and a removable center casting or filler comprising a bottom member formed with a center bearing and two disunited upright members adapted to be fitted into the transom.

4. In a car-body underframe, the combination with a transom having central separated recesses, center sills, a center casting comprising a bearing-plate and disunited upright members, said members of such form that when assembled with the center sills rectangular projections are formed which are adapted to fill the recesses.

5. In a car-body-underframe construction, the combination with two center sills of channel form, a transom provided with separated recesses to receive the center sills, and a removable center casting formed with disunited upright members each provided with

inclined ledges; said upright members fitted 20 into the center sills.

6. In a car-body-underframe construction, the combination with two center sills of channel form, a transom formed with separated recesses to receive the center sills and with 25 projections extending into the recesses, a removable center casting formed with disunited upright members each provided with inclined ledges and a groove or pocket, the latter being adapted to receive the said projections on the transom.

In testimony whereof I affix my signature in presence of two subscribing witnesses.

OSWALD S. PULLIAM.
